(57) **CLAIM**

The ornamental design for the rear panels for SUV conversion kit, as shown and described.

DESCRIPTION

FIG. 1 is a rear perspective view of rear panels for an SUV conversion kit showing my new design;

FIG. 2 is a right elevational view of rear panels for an SUV conversion kit in FIG. 8;

FIG. 3 is a left elevational view of rear panels for an SUV conversion kit in FIG. 8;

FIG. 4 is a rear elevational view of rear panels for an SUV conversion kit in FIG. 8;

FIG. 5 is a front elevational view of rear panels for an SUV conversion kit;

FIG. 6 is a top plan view of rear panels for an SUV conversion kit in FIG. 8;

FIG. 7 is a bottom plan view of rear panels for an SUV conversion kit;

FIG. 8 is a left elevational view of rear panels for an SUV conversion kit in FIGS. 1 and 8; and,

FIG. 9 is a partial rear elevational view of rear panels for an SUV conversion kit in FIGS. 1 and 8.

The broken phantom lines depict unclaimed subject matter only and form no part of the claimed design.

1 Claim, 7 Drawing Sheets
